UNITED STATES PATENT OFFICE.

SAMUEL GOLD, OF CHICAGO, ILLINOIS, AND LOA B. CONDUIT, OF MEDINA, OHIO.

DESIGN FOR A BOY'S COAT.

Application filed August 16, 1928. Serial No. 27,831. Term of patent 14 years.

To all whom it may concern:

Be it known that we, SAMUEL GOLD and LOA B. CONDUIT, citizens of the United States, residing at Chicago, in the county of Cook and State of Illinois, and Medina, in the county of Medina and State of Ohio, respectively, have invented a new, original, and ornamental Design for Boy's Coat, of which the following is a specification, reference being had to the accompanying drawing, forming part thereof.

Figure 1 is a front view of the boy's coat showing our new design.

Fig. 2 is a perspective rear view.

We claim:

The ornamental design for a boy's coat as shown.

SAMUEL GOLD.
LOA B. CONDUIT.
